SADIIRON CONSTRUCTION

Howard Smith, Belleville, Ill., assignor to Knapp-Monarch Company, St. Louis, Mo., a corporation of Missouri

Application January 28, 1935, Serial No. 3,748

13 Claims. (Cl. 219—25)

The object of my invention is to provide a sadiron construction, which is simple, durable and comparatively inexpensive to manufacture.

A further object is to provide a sadiron construction having novel means for retaining a heating element on the sole plate in such position that the maximum of heat is transmitted therefrom to the sole plate and for insulating the ends of the heating element from the sole plate and weight

10 member of the iron.

A further object is to provide a terminal member for the ends of the heating element, having terminal pins with which the ends of the heating element are associated in a novel manner, the terminal member being retained in position by means of lugs formed therein engaging notches in the shell of the iron.

Still another object is to provide a combined rest and terminal protector member which is 20 readily connected with the iron by means of a part interposed between the shell and sole plate of the iron and another part held in position by one of the nuts which holds the shell of the iron in position, this member also having a handle 25 arm with which one end of the handle for the iron can be connected.

With these and other objects in view my invention consists in the construction, arrangement and combination of the various parts of my device, whereby the objects contemplated are attained, as hereinafter more fully set forth, pointed out in my claims and illustrated in the accompanying drawings, in which:

Figure 1 is a side elevation of a sadiron construction embodying my invention showing it in rest position.

Figure 2 is a vertical, central sectional view through the iron showing it in ironing position.

Figure 3 is a sectional view on the line 3—3 of 40 Figure 2 showing the sole plate with the heating element associated therewith.

Figure 4 is a sectional view on the line 4—4 of Figure 2 showing a bottom plan view of the shell, terminal member and combined rest and terminal protector.

Figure 5 is an enlarged sectional view on the line 5—5 of Figure 3.

Figure 6 is a sectional view similar to the right 50 end of Figure 2 showing some of the parts being assembled.

Figure 7 is a bottom plan view of the terminal member as viewed in the direction of the arrow 7 of Figure 6.

55 Figure 8 is a perspective view of one of the

terminal pins with the end of the heating element resting in a slot thereof.

Figure 9 is a similar view showing the slot deformed to retain the heating element end in position.

Figure 10 is a sectional view, enlarged, on the line 10—10 of Figure 9 showing how the end of the heating element is clamped in the terminal pin.

Figure 11 is a sectional view on the line 11—11 of Figure 3 showing the parts enlarged.

Figure 12 is a perspective view of the rear portion of the shell showing the terminal member associated therewith and part of the combined rest and terminal protector separated from the shell and terminal member; and

Figure 13 is a separated perspective view of the combined rest and terminal protector which is formed in two parts.

On the accompanying drawings I have used the reference numeral 10 to indicate a sole plate. The sole plate 10 is provided with a double spiral groove 12 in which a heating element 14 is laid. The heating element 14 may be of the type having a coil 14a of resistance wire embedded in insulating material which is initially plastic but becomes hardened upon being heated. As shown in Fig. 5, each stretch of the heating element 14 has its own groove 12 and these are separated by a wall 16 formed of the sole plate material and extending up between the stretches of the heating element, thus providing a maximum heat absorbing surface for the heating element as distinguished from relatively wide grooves in which the stretches of the heating element are wound side by side.

At the ends of the heating element 14 sockets 18 are provided (see Figure 11). Within each socket 18 I provide an insulating disc 20 made of porcelain, Lavite or the like, and a bushing 22 also of insulating material. The bushing 22 has a central perforation 24 and a radially extending groove 26. The end of the resistance wire 14a is preferably doubled as indicated at 14c and extends through the groove 26 and the perforation 24.

The bushing 22 has a sleeve-like extension 28. A weight member 30 is superposed on the sole plate 10 and retains the heating element 14 in position. The weight member 30 has a perforation 32 for each sleeve-like extension 28 of the bushing 22.

Bolts 34 and nuts 36 are provided for retaining the weight member 30 in position on the sole plate. These are retained in threaded openings 55

38 of the sole plate. A shell 40 is retained in position covering the weight member 30 by nuts 42 which are threaded on to the upper ends of the bolts 34. Lugs 38, 41 and 43 are provided for positioning the shell relative to the sole plate.

5 A terminal member A, shown separated from the rest of the sadiron in Figure 7, is provided. It comprises a supporting element 44 made of sheet metal or the like which supports terminal pins 46 in position suitably insulated with respect to the element 44. Heads 48 are provided on the pins 46 and lock nuts 50 are screwed on to the pins for retaining them rigidly in position on the supporting element 44.

10 15 The heads 48 are slotted as indicated at 52 and originally these slots are open as they appear in Figure 8 and as in the upper half of Figure 7.

20 The heating element end 14c is inserted in the slot 52 and then the head 48 is deformed crosswise of the slot as indicated at 54 in Figure 9 and as in the lower half of Figure 7. This deformation closes the slot around the heating element end 14c as best shown in Figure 10, thus making a good 25 mechanical and electrical connection between the terminal pin and the end of the heating element.

25 30 The supporting element 44 has a reduced lug 56 at one end and a reduced lug 58 at the other end. The shell 40 has a notch 60 to receive the lug 56 and a notch 62 to receive the lug 58. The lug 56 is angle-shaped as shown in Figure 6, thus providing a shoulder at 64, while the lug 58, also being angle-shaped provides a shoulder or 35 surface 66. These shoulders are engageable with the sides of the notches 60 and 62 to prevent lateral displacement of the terminal member relative to the notches.

40 45 A combined rest and terminal protector B is provided. It is formed in two parts as shown in Figure 13, one part having the doubled flanges 68 and 70 forming a rest leg and also having a second rest leg 12, a handle arm 74 and an attachment lug 76.

50 55 The second part has a plate-like portion 78, on which the name of the iron or other data may be stamped, and flanges 80 and 82 serving in conjunction with the parts 68 to 76 inclusive to encase the terminal pins 46. The stamping 60 forming the parts 78, 80 and 82 is provided with bendable ears 84 and 86 for attaching this part to the flange 70 of the other part. Perforations 88 are provided for the ears 84, while the ear 86 coacts with the rear edge of an opening 90, formed 65 in the flange 78.

65 70 The flange 88 is provided with a T-shaped lug 92 (see Figure 12). The notch 62 in the shell 40 is made deep enough to receive both the lug 92 of the terminal member A and the lug 92 of the combined rest and terminal protector B.

75 The head of the T-shaped lug 92 prevents rearward displacement of the flange 88 relative to the shell 40.

80 85 During assembly the terminal member A is placed in position as shown in Figure 6 and then the member B is placed so that the lug 92 thereof is in its proper position. The member B may then be swung about the notch 62 as a pivot, as shown by the arrow a in Figure 6, until the attachment lug 76 rests on the shell 40 as shown in Figure 2. The rearward nut 42 for the shell can then be placed in position and the flange 88 of the member B will be retained between the shell and sole plate while the lug 76 will, of course, be retained by the nut 42. Thus a sim-

ple means is provided for assembling the parts A and B together by manipulation of but one attaching member (the rear nut 42).

85 90 A handle 94 is provided for the sadiron. A handle arm 96 is retained by the forward nut 42 and the handle 94 is mounted on the arm 14 of the member B and the arm 96. Screws 98 may be provided for this purpose.

95 100 The rest leg 12 of the member B is provided with an opening 100. The openings 90 and 100 provide for insertion of the plug 102 of a cord set, as shown by dotted lines in Figure 2. The flanges 80 and 82 surround the plug 102 and in conjunction with the rest leg 12 protect the terminal pins 46 from being touched by the operator while the plug 102 is being inserted, thus serving as a protection against shock.

105 110 The leg 12 and part of the flange 70, it will be noted are provided with reinforcing flanges 104 to strengthen these parts and prevent undesired bending thereof.

115 120 I have provided a sadiron construction having several novel features making the iron more "fool proof" by providing adequate insulation for the ends of the heating element and connecting 125 these ends with the terminal pins. The iron is also readily assembled without the necessity of using a multiplicity of connecting elements. The parts so interfit that when the shell is finally 130 fastened in position the terminal member A and the rest and terminal protector B are rigidly retained in position against any possible accidental displacement.

135 140 Some changes may be made in the construction and arrangements of the parts of my device without departing from the real spirit and purpose of my invention and it is my intention to cover by my claims any modified forms of structure or use of mechanical equivalents which may be reasonably included within their scope. 145

I claim as my invention:

150 1 In a sadiron construction, a sole plate, a heating element for said sole plate, a shell for covering said sole plate and heating element and a terminal member for the ends of said heating element comprising a supporting element, terminal pins supported thereby, the upper and lower ends of said supporting element having reduced lugs, said shell having an opening to be closed by said element, a notch in the side of said opening to receive said upper lug, the lower edge of said shell having a notch for said lower lug, said upper lug being retained against disassociation from its notch when said lower lug is in its notch and said lower lug being retained in its notch by 155 said sole plate when said shell is assembled thereon.

160 2 In a sadiron construction, a sole plate, a heating element for said sole plate, a shell for covering said sole plate and heating element and a terminal member for the ends of said heating element comprising a supporting element, terminal pins supported thereby, said shell having an opening to be closed by said element, a notch in the edge of said opening and a notch in the 165 lower edge of said shell to receive the ends of said supporting element, said sole plate, when said shell is assembled in position thereon, retaining said supporting element in position relative to said sole plate and said shell. 170

175 3 In a sadiron construction, a sole plate, a heating element and a shell for said sole plate, a terminal member for the ends of said heating element comprising a supporting element, terminal pins supported thereby, said shell having an 180

opening for said terminal pins and having notches, one in the edge of said opening and one in the peripheral edge of said shell to receive the ends of said supporting element, said supporting element having shoulders to engage said shell adjacent said notch in the edge of said opening to thereby position said supporting element relative to said shell, said sole plate, when said shell is assembled in position thereon, retaining said supporting element in position.

4. In a sadiron construction, a sole plate, a heating element therefor, a shell for enclosing said heating element, terminal pins for the ends of said heating element, a combined rest and terminal protector for said terminal pins, said protector being formed of a sheet of metal bent Z shape and having enlarged openings through the upper two adjacent legs thereof to completely surround said terminal pins and receive a terminal plug coacting therewith, and means for securing said shell to said sole plate, said rest and terminal protector having a part retained between said shell and said sole plate and another part secured in position by said means.

5. In a sadiron construction, a sole plate, a heating element therefor, a shell for enclosing said heating element, terminal pins for the ends of said heating element, a combined rest and terminal protector for said terminal pins, said rest and terminal protector comprising a pair of rest legs formed of sheet metal bent Z shape, one of said legs constituting an encircling portion for a supply cord plug when coacting with said pins, the upper two adjacent legs having enlarged openings therein completely surrounding said pins and plug, and means for securing said shell to said sole plate, said rest and terminal protector having a part secured in position by said means.

6. In a sadiron construction, a sole plate, a heating element therefor, a shell for enclosing said heating element, terminal pins for the ends of said heating element, a combined rest and terminal protector for said terminal pins, said rest and terminal protector comprising a single piece of sheet metal formed to provide a rest portion, at least one portion for encasing a supply cord plug when coacting with said pins, and a handle supporting arm, a handle for said sadiron having one end connected with said handle arm and supported thereby, and means for securing said shell to said sole plate, said rest and terminal protector having a part retained between said shell and said sole plate and another part secured in position by said means.

7. In a sadiron construction, a sole plate, a heating element therefor, a shell for enclosing said heating element, terminal pins for the ends of said heating element, a combined rest and terminal protector for said terminal pins, said rest and terminal protector comprising a pair of rest legs formed of sheet metal and bent V shape, one of said legs constituting an encasing portion for a supply cord plug when coacting with said pins, said legs having enlarged openings adjacent the apex of the V completely surrounding said pins and plug, means for securing said shell to said sole plate, said rest and terminal protector having a part retained between said shell and sole plate and another part secured in position by said means.

8. In a sadiron, a sole plate, a heating element therefor, a shell enclosing said heating element, a terminal member for the ends of said heating element, a combined rest and handle supporting

arm for said iron, and means for securing said shell to said sole plate, said rest and handle supporting arm comprising a sheet of metal bent V-shape, having a pair of aligned openings in the arms thereof adjacent the apex thereof, having the handle supporting arm thereof extending upwardly from said apex, and having a part secured in position by the aforesaid means.

9. In a sadiron construction, a sole plate, a heating element for said sole plate, a shell for covering said sole plate and heating element, means for securing said shell to said sole plate, a terminal member for the ends of said heating element having terminal pins supported thereby, a combined rest and terminal protector for said terminal member comprising a member extending in a plane which is inclined upwardly and rearwardly from a position on said shell forwardly of said terminal pins, said member having an enlarged opening surrounding said terminal pins and adapted for reception of a connector plug coacting therewith, and a portion of said rest and terminal protector being adapted to be secured in position by the aforesaid securing means.

10. In a sadiron construction, a sole plate, a heating element for said sole plate, a shell for covering said sole plate and heating element, a terminal member for the ends of said heating element having terminal pins supported thereby, a combined rest and terminal protector, said rest and terminal protector comprising a pair of rest legs arranged in V-shape, a terminal encasing portion constituted by one of said legs, openings through said legs adjacent the apex of the V through which a terminal plug may extend, a notch in the edge of said shell and a portion on said rest and terminal protector adapted to coact with said notch, said portion being retained in said notch when said shell is assembled in position on said sole plate.

11. In a sadiron construction, a sole plate, a heating element for said sole plate, a shell for covering said sole plate and heating element and a terminal member for the ends of said heating element comprising a supporting element, terminal pins supported thereby, the ends of said supporting element having reduced lugs, said shell having notches to receive said lugs, one of said lugs being retained against disassociation from its notch when the other lug is in its notch and said other lug being retained in its notch by said sole plate when said shell is associated therewith, and a combined rest and terminal protector for said terminal member, said rest and terminal protector having a part retained between said shell and said sole plate, said terminal member being interposed between said part and said shell.

12. In a sadiron construction, a sole plate, a heating element for said sole plate, a shell for covering said sole plate and heating element and a terminal member for the ends of said heating element comprising a supporting element, terminal pins supported thereby, said shell having an opening and a notch in the edge of said opening to receive the upper end of said supporting element, the lower end thereof being interposed between said sole plate and the edge of said shell and retained thereby when the two are assembled relative to each other.

13. In a sadiron, a sole plate, a heating element, a shell, terminals for said heating element and a combined rest, handle supporting and terminal protecting member, said member comprising a pair of rest legs arranged in V-shape, a

terminal encasing portion constituted by one of said legs, openings through said legs adjacent the apex of the V, a handle supporting arm extending upwardly from said apex, a handle having one end supported by said arm, means for securing said shell to said sole plate, a notch in the edge of said shell and a portion on said mem-

ber adapted to coact with said notch, said portion being retained in said notch when said shell is assembled in position on said sole plate and another portion of said member being secured in position by the aforesaid securing means. 5

HOWARD SMITH.
